Attorney

UNITED STATES PATENT OFFICE.

JOHN EDWARD GLOEKLER, OF PITTSBURGH, PENNSYLVANIA.

REFRIGERATOR.

Application filed July 13, 1926. Serial No. 122,093.

My invention refers to improvements in refrigerators, more particularly to those utilizing artificially generated refrigeration by means of a localized refrigerating unit.

5 It has in view to provide an enclosing air circulating chamber for such unit, properly located with relation to the remainder of the refrigerator body and its food etc. containing compartments, and embodying 10 certain features providing for closure, access, moisture collection, etc. as hereinafter more fully set forth.

Referring to the drawing showing one preferred embodiment of the invention:

15 Fig. 1 is a view in front elevation of a portion of a refrigerator, embodying the invention;

Fig. 2 is a horizontal section on the line II, II, of Fig. 1;

20 Fig. 3 is a vertical cross section on the line III, III, of Fig. 2;

Fig. 4 is a vertical section on the line IV, IV, of Fig. 1;

25 Fig. 5 is a detail view in perspective of the removable cover lid of the front wall of the refrigerating chamber.

In the drawing, 2 is one of the outer side walls, 3 the back wall, and 4 the top of a standard refrigerator, of the usual insulated 30 type. In such constructions one or more preserving or food containing compartments 5 are provided, usually with supporting racks 6 for placement of articles, within the refrigerating zone of a temperature-reducing or air refrigerating chamber A.

35 In the present construction chamber A is isolated from such chamber at the upper portion of the construction by a sheet metal partition 7 extending from the back wall 3 forwardly to a front partition plate 8 of sheet metal, forming the front wall of the chamber.

Side wall or partition 7 extends upwardly to within a short distance of the top 4 with 40 an intervening space 9 for inward circulation of high temperature air from the top of adjacent chamber 5 to refrigerator unit chamber A. The bottom of said chamber is closed by a drip pan 10, which extends from the back wall 3 to the front closing wall plate 8 and from partition 7 towards the opposite side wall 2.

45 The drip pan however extends only partially across the bottom of chamber A, leaving a space 11 for downward circulation of

cold or low temperature air in its progress towards the lower food compartment.

Pan 10 is loosely supported on rear angle bracket 12 of the rear wall and a similar bracket or flange 13 at the bottom of front 60 wall 8, providing for easy removal and placement from underneath.

A refrigerating unit *a*, which is of any suitable or usual type for absorption of heat units from the air, is located about the 65 middle of chamber A and in the path of the air currents coming inwardly through opening 9 and passing outwardly through opening 11.

Unit *a* is supported within the chamber 70 cavity by means of suitable straps or hangers 14 from the top 4 or otherwise as preferred.

The refrigerating unit of the construction shown is provided with one or more ice cake holding drawers or pans 15, inserted inwardly and removable outwardly from the interior of the unit, as is well understood.

For the purpose of access to the unit and for manipulation of such pans, the front wall 8 is provided with a rectangular opening 80 of ample size to allow for passage of the pans therethrough. The opening is closed by a cover plate 16 removably mounted by an upper terminal lip 17 engaging the upturned supporting edge 18 of the front 85 wall 8, as in Fig. 4.

Plate 16 is provided with a small finger hole opening 19 by which it may be lifted off and replaced, the hole being of such reduced size as to prevent any material circulation therethrough.

As thus constructed, the front wall 8 and its cover plate completely isolate the refrigerating chamber A from the front, so that when the main door or doors 20, indicated in dotted lines in Fig. 2, are open, there will be no exposure of the chamber.

It is therefore continuously maintained in a comparatively isolated protected condition at all times.

The drip pan 10 collects any moisture of condensation, which may be removed from time to time by merely reaching in beneath the lower edge of the front wall 8. Its location insures the prevention of any moisture from falling downwardly to the lower compartment, while also providing a circulation obstruction, and insuring diagonal circulation of the air downwardly through chamber A, as indicated in Fig. 3.

110

It will be understood that the detail construction of the main refrigerator casing is of any preferred or standard type, as to insulating walls etc., and that the incorporation of the refrigerating chamber and its features is independent of any particular or special location, arrangement or connection.

It may be of various sizes and dimensions 10 to suit the main refrigerator body, and may be changed or varied in its detail construction by the skilled mechanic or builder to adapt it to existing conditions of construction or use.

15 The invention provides a simple, convenient, and advantageous feature in connection with refrigeration of the modern kind, and is economical in operation and extremely efficient.

20 What I claim is:—

1. The combination with a refrigerating chamber having surrounding back, side, top, and bottom walls, with a vertical sheet metal partition extending forwardly from the back wall with its upper edge spaced below the top wall, and a removably mounted transverse drip pan extending from the lower inner bottom portion of said partition towards the side wall with an intervening space thereby providing upper and lower diagonally located air circulation openings, and a refrigerating unit suspended in said chamber having removable ice containing holders; of a front wall of the full depth of 25 said partition extending therefrom to the side wall provided with an opening for access to said chamber and an outer removable covering plate therefor having a finger opening.

30 2. The combination with a refrigerating

chamber having surrounding back, side, top, and bottom walls, with a vertical sheet metal partition extending forwardly from the back wall with its upper edge spaced below the top wall, and a removably mounted transverse drip pan extending from the lower inner bottom portion of said partition towards the side wall with an intervening space thereby providing upper and lower diagonally located air circulation openings, 45 and a refrigerating unit suspended in said chamber having removable ice containing holders; of a front wall of the full depth of said partition extending therefrom to the side wall provided with an opening for access to said chamber and an upwardly turned supporting edge above the opening, and an outer removable covering plate for the opening having at its top a downwardly turned supporting edge and a finger opening. 50

3. The combination with a refrigerating chamber having surrounding back, side, top and bottom walls, with a vertical sheet metal partition extending forwardly from the back wall with its upper edge spaced below the top wall, and a removably mounted transverse drip pan extending from the lower inner bottom portion of said partition towards the side wall with an intervening space, thereby providing upper and 55 lower diagonally located air circulation openings, and a refrigerating unit suspended in said chamber; of a front wall of the full depth of said partition extending therefrom to the side wall provided with an opening for access to said chamber, and an outer removable covering plate. 60

In testimony whereof I hereunto affix my signature.

JOHN EDWARD GLOEKLER.
